CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE

SHEET METAL CONTAINER

Application filed October 3, 1930. Serial No. 486,078.

This invention relates broadly to sheet metal containers, and more specifically to that type of can or drum which embodies in the head end a removable cover and which are commonly employed as containers for greases and other semi-solid materials.

The primary object of the invention is to provide a container of the character mentioned embodying a cover of the self-retaining lug type which, following its release, effected by outward bending of its lugs, remains attached at one side to the head of the container through a hinge-like connection and which, therefore, may be swung to and from its closing position as and when occasion arises.

It will be understood that, in the use of grease containers of this general type having covers which are completely detachable, such covers are frequently cast aside and, through carelessness on the part of users, or because of distortion thereof resulting from mishandling, are not replaced from time to time. In such cases, dirt, grit and other foreign matter deleterious or ruinous to the contents are readily admitted.

The present invention is designed to provide a cover which, though it may be wholly detached when desired, need not necessarily be removed to permit access to the contents, being attached to the container head in such manner that it may readily be swung to and from an upright position with respect to the head, as upon a hinge.

A further object is to provide, in a container of the character mentioned, a cover which, following an initial thrust or push applied thereto, is automatically actuated to return from its upright position to its lowered closing position, and which, consequently, does not require that it be carefully fitted in placed by hand.

In describing the invention in detail, reference is herein had to the accompanying drawing, in which—

Figure 1 is a vertical section of the head end of a container embodying my invention, showing the cover occupying closing position;

Figure 2 is a similar view with the cover occupying elevated position;

Figure 3 is a sectional elevation, the section being taken at right angles to the section shown in Figs. 1 and 2; and—

Figure 4 is a detail section illustrating a modified form.

Referring to said drawing, 1 designates the container body, and 2 a head which is permanently attached to said body. Said head has an upstanding neck 3 defining an opening through which access is had to the interior of the container for the introduction and removal of the contents. Said neck 3 preferably embodies an outwardly turned terminal bead or roll 4 upon which may be seated the upwardly, outwardly and downwardly turned seating flange 5 of a cover 6 designed to serve as a closure for the neck defined opening mentioned. The cover 6 embodies a plurality of integral relatively spaced lugs 7 which depend from the flange 5 and which, during shipment and storage, are tucked into underlying cover-securing relation to the roll 4 of the neck 3, as ordinarily.

Rigidly attached to the under side of the cover 6 adjacent to one side thereof is an end 75 of a flexible leaf spring 8 of flat tongue-like form which, in the lowered seating position of said cover, has the body portion thereof occupying a downwardly and outwardly inclined position wherein it lies at a distance 80 below the adjacent edge portion of the head 2. The outer end portion of said springs is curved upwardly to lie approximately at a right angle to the body thereof and engages said head, as shown. A transverse upwardly pressed crimp or rib 9 formed in the free end portion of said spring is received in an upwardly-indented channel-like seat 10 provided therefor in the under side of said head 2.

In the upright position of the cover, as shown in Figs. 2 and 3, the spring 8 has the rib 9 thereof retained within the channel 10, while a substantial intermediate portion of the length of the spring rests against and is supported by or against the adjacent wall of the neck 3 of the head. So positioned, the spring exerts a force which tends to maintain the cover more or less rigidly against movement. When, however, said cover has been

100

forcibly moved toward closing position throughout a relatively short distance, said spring is placed under a tension which exerts a force in the direction of the movement and completes the closing movement with considerable rapidity, or with a snap.

In its upright open position, the cover is supported by the spring with its seating flange 5 partially removed from the terminal roll 4 of the neck 3 and occupies substantially the position shown in Fig. 2 wherein the angle between the cover body and said flange rests upon said roll. As the cover returns to its closing position, the flange 5 resumes its seated relation to said roll.

A resilient latch 11 is preferably carried on the edge of the under side of the cover diametrically opposite the location of the spring 8, said latch being designed to yieldingly interengage the head 2 at the angle between the latter and the neck 3, as shown in Fig. 1. Said latch may, if preferred, be formed as an integral part of the spring 8, a strap-like member 12 attached to the under side of the cover, as by spot welds, having said latch and said spring formed on the opposite ends thereof.

A suitable handle, as the wire ring 13, may be mounted on the top of the cover 6 adjacent to the edge of the latter at a point opposite the spring 8, said handle providing means whereby the cover may be grasped for raising to its open position.

In the modification illustrated in Fig. 4 the head 2^a has a downwardly directed neck 3^a defining the opening thereof, and the cover 6^a is provided with an annular seating flange 5^a adapted to rest upon the top surface of said head. The spring 8^a, which may have its end shaped to form a terminal bead or roll 9^a, rather than the rib shown in Figs. 1, 2 and 3, occupies seated underlying relation to the head and is preferably shiftable on said head toward and away from the neck 3^a in opening and closing of the cover. With this construction the channel-like seat 10 may be omitted from the head. Manifestly, chance disengagement of said cover from the head is prevented by the interengagement of said spring with the neck 3^a.

The spring, interengaged with the head of the container as described, constitutes a hinge-like connection which possesses the advantages that no part thereof is rigidly or permanently attached to the head of the container, that it permits the cover to be wholly detached from the container when occasion requires, that it functions to forcibly return the cover to closing position following an initial shifting of the cover toward said position, and that it serves to yieldingly maintain said cover in its full open position after elevation thereof.

What is claimed is—

1. A sheet metal container comprising a body having a head, said head being provided

with an opening defined by a neck of flange form, a cover for said opening having a seating flange, a resilient member mounted on the under side of and wholly supported by said cover, said member having an end portion thereof extended into underlying relation to an adjacent portion of said head and having an angularly disposed terminal portion disposed in underlying seated engagement with said head, said member constituting a hinge-like connection between said cover and said head and being adapted to exert a yielding force tending to retain said cover against movement from either its seated or its upright position.

2. A sheet metal container comprising a body, a head attached to said body and having therein an opening defined by an angularly disposed neck, a cover for said opening having a seating flange for resting upon said neck, a resilient member carried on the under side of said cover and having an end portion thereof extended into underlying pivotally seated relation to a portion of said head, said member constituting a hinge-like connection between said cover and said head and being adapted to exert a yielding force tending to retain said cover against movement from either its seated or its upright open position.

3. A sheet metal container comprising a body, a head attached to said body and having therein an opening defined by an upright neck, a cover for said opening having an outwardly turned seating flange, a spring of flat tongue-like form attached to said cover and having an end inclined downwardly and outwardly into underlying relation to said head, said end having therein a transverse upwardly pressed rib and said head having therein an upwardly indented seat with which said rib is interengaged, said cover being adapted to swing on said spring to and from upright position wherein an intermediate portion of said spring rests against said neck, said spring being placed under tension and exerting a yielding force which tends to retain the cover against movement either from its seated or its upright position.

4. A sheet metal container comprising a body, a head attached to said body and having therein an opening defined by an upright neck, a cover for seating within said neck, a resilient tongue-like member carried on the under side of said cover, said member in the seated position of said cover extending downwardly and outwardly beneath said head and having its end portion bent upwardly into underlying seated relation to said head, said end portion having therein a transverse rib and said head having therein an upwardly indented seat with which said rib is interengaged, said cover being adapted to swing relative to its said seated position to and from an upright position, said resilient mem-

ber being placed under a tension in each of its opposite positions which tends to resist movement from the latter.

5. A sheet metal container comprising a body, a head attached to said body and having therein an opening defined by an upright neck, a cover for seating within said neck, a flat tongue-like spring carried on the under side of said cover, said spring in the seated position of said cover extending downwardly and outwardly beneath said head, said head having therein an upwardly indented seat, and said spring having a terminal portion interengaged with and adapted 10 for rotary movement on said seat, said cover being adapted for movement relative to its seated position to and from an elevated position wherein an intermediate portion of 15 said spring occupies seated cover-supporting relation to said neck, said spring in each of 20 the opposite positions of said cover being placed under tension which tends to resist movement.

6. A sheet metal container comprising a body having a head, said head being provided 25 with an opening defined by a neck flange, a cover adapted to fit within said neck in closing relation to said opening, a resilient member carried on the under side of said cover 30 and having its body inclined downwardly into underlying relation to said head, said body having its terminal portion bent to lie at an angle thereto and occupying seated 35 relation to said head adjacent to said neck flange, said member forming a hinge-like connection between said cover and said head and, at each of its opposite limits of movement, 40 yieldingly resisting movement therefrom.

In testimony whereof, I affix my signature.

CHARLES H. ROLLASON.
